CLAIM

We claim the ornamental design for a sprayhead, as shown and described.

DESCRIPTION

FIG. 1 is a top perspective view of the claimed design;

FIG. 2 is a top view thereof;

FIG. 3 is a bottom view thereof;

FIG. 4 is a right side view thereof, the left side view is a mirror

image of FIG. 4; and,

FIG. 5 is a front view thereof.

The broken lines in the drawings are for illustrative purposes only and form no part of the claimed design.

1 Claim, 3 Drawing Sheets
